SWITCH HOUSING

Nathan Verger, Great Neck, N. Y.

Application June 7, 1956, Serial No. 41,804

Term of patent 14 years

(Cl. D26—13)

FIG. 1.

FIG. 3.

FIG. 2.

FIG. 4.

FIG. 5.

FIG. 6.

Figure 1 is a front elevational view of a switch housing showing my new design;

Figure 2 is an end elevational view thereof;

Figure 3 is a side elevational view thereof;

Figure 4 is an elevational view of the opposite side thereof;

Figure 5 is an elevational view of the opposite end thereof; and

Figure 6 is a rear elevational view thereof.

I claim:

The ornamental design for a switch housing, substantially as shown.
